OTTO FEUERLEIN, OF CHARLOTTENBURG, AND MARCELLO VON PIRANI, OF WILMERSDORF, GERMANY, ASSIGNEES, BY MESNE ASSIGNMENTS, TO GENERAL ELECTRIC COMPANY, A CORPORATION OF NEW YORK.

PROCESS OF MOUNTING METALLIC FILAMENTS ON FILAMENT-CARRIERS OF INCANDESCENT LAMPS.

1,144,114.

Specification of Letters Patent. Patented June 22, 1915.

Application filed July 21, 1910. Serial No. 573,058.

To all whom it may concern:

Be it known that we, OTTO FEUERLEIN, a subject of the German Emperor, and residing at Charlottenburg, near Berlin, Germany, and MARCELLO VON PIRANI, a subject of the King of Italy, and residing at Wilmersdorf, near Berlin, Germany, have invented a certain new and useful Improved Process of Mounting Metallic Filaments on Filament-Carriers of Incandescent Lamps, of which the following is a specification.

Our invention relates to the manufacture of metallic filament incandescent lamps.

It is preferable to employ as thin filament holders as possible for incandescent lamps having metallic filaments particularly in order to be able to fuse as large a number as possible of the holders at a sufficient distance apart in as small glass beads as possible, in order to diminish the conduction of heat from the filaments. In incandescent lamps, in which a continuous metal wire is wound on the filament holders, one is limited however in the selection of the thickness of the holders, because thin holders do not stand the mechanical strains when being wound and bent. Therefore when very thin holders are employed it is impossible to dispose the filament uniformly.

According to our invention thin, only slightly elastic, but pliable filament holders can be employed in the manufacture of incandescent lamps comprising wound metal wires, if the holders are relieved when the metal filament is being wound. To this end, the holders are supported by auxiliary means and the incandescent filament is then wound in the customary manner. Owing to the winding the filament obtains a certain tension, under the influence of which it would contract the holders as soon as they are removed from the supporting device. In order to prevent this the filament is heated by a current passed through it before its release from the holders. The heating may take place in the open air and a short rush of current suffices. The filament completely loses its tension and remains without tension in the position given to it.

Instead of supporting the thin holders by a special device, when the filament is being wound they may be relieved by simultaneously employing stronger holders, whose sole

purpose is to give the necessary resistance during the winding operation. When the winding is completed the incandescent filament is distended in like manner by a current and the strong holders are bent back so that the filament is finally supported only by the thin holders.

A modified mode of carrying our process into practice consists in placing the metal filament firstly over firm hooked members which are connected with the yielding holders for the final support of the filament. After the desired shape has been given to it the filament is transferred from the firm to the yielding holders.

One form of filament carrier comprising one form of filament holder for carrying our process into practice is represented by way of example in perspective in the accompanying drawing.

Referring to the drawing, *a* designates the more resisting portion and *b* the very pliable portion of a filament holder. The bend *c* in the firm part *a* serves for the winding of the wire, and the bend *d* in the pliable part for receiving the wire after it has been wound. In order to transfer the wire from the bend *c* to the bend *d* the entire carrying arm or holder is bent downward somewhat and replaced into its original position after the transference has been effected. Before the transference of the filament the wire is distended by an electric current, as described above.

We claim:

1. The process of mounting continuous metallic filaments, which comprises winding the filament back and forth and resisting the tension of the wire by rigid supporting means, passing electric current through the filament to distend it, and subsequently causing the filament to be supported by thin pliable holders.

2. The process of mounting continuous metallic filaments on thin pliable filament holders unable to resist the strain of winding the filament, which comprises winding the filament over holders rigidly supported against bending under the strain of winding the filament, and thereafter rendering the pliable holders the sole support of the filament.

3. The process of mounting continuous

metallic filaments upon thin pliable holders unable to resist the strain of winding the filament, which comprises winding the filament over the holders while the tension of the winding is resisted by rigid supporting means, passing current through the filament to distention it, and thereafter rendering the filament free of the rigid supporting means and dependent upon the pliable holders.

4. The process of mounting continuous metallic filaments on holders which comprises winding the filament preliminarily over firm sections of holders, each holder comprising a firm section and a pliable section, passing current through the filament to distention the same and subsequently transferring the filament to the pliable section of the holder.

5. The process of mounting continuous metallic filaments which comprises winding the filament over the firm section of a permanent holder comprising firm and pliable sections, passing current through the filament to distention it and bending the individual arms of the holders inward to free the filament, transferring the filament to

the pliable section of the holders attached to the free ends of the firm section thereof and finally bending the individual arms of the holders back into their original position.

6. The method of mounting a filament on yielding holders each comprising a rigid resisting part and a yielding tip, which consists in winding the filament on the resisting part of the holder and subsequently transferring the filament to the tip of the holder by which it is finally supported.

7. The process of mounting continuous filaments on holders having a relatively rigid portion and a relatively elastic portion which consists in stringing said filament on the rigid portion, heating it to give it a set, and transferring the filament to the elastic portion.

In testimony whereof we have signed our names to this specification in the presence of two witnesses:

OTTO FEUERLEIN.
MARCELLO VON PIRANI.
